RACKET FOR TENNIS AND LIKE GAMES

Emile Henri Aubert, Paris, France, assignor to
 Société pour la Réalisation et l'Exploitation
 d'Inventions Mécaniques "Reim," Neuilly sur
 Seine, Seine, France

Application October 31, 1938, Serial No. 238,089
 In France November 5, 1937

2 Claims. (Cl. 273—73)

- The present invention relates to rackets for tennis and like games, of the type in which the string network is supported by two opposed supple or articulated flexible bands or like members, adapted to be slidden along the frame by means of an operating device mounted in the throat piece of the racket and adapted to exert a traction upon these two bands or like members, to stretch or slacken the string network.
- 5 Rackets of this type are known in which said bands or like members are flexible over their entire length and said operating device is constituted for example by a screw having two parts threaded in contrary directions and screwed into
- 10 two nuts connected to the bands or like members and slidably guided within a transverse aperture of the throat-piece of the racket. In this arrangement said nuts are liable to wedge in said transverse aperture thereby preventing their free
- 15 20 sliding in said aperture.

The present invention has for its object to provide a racket of the above-mentioned general type and improved to ensure a better sliding of the bands along the frame. According to the invention, each of the flexible bands or like members supporting the string network comprises at its end adjacent the throat piece of the racket a rigid circularly curved shoe of relatively great length and the frame is formed with a corresponding circular surface having the same radius and against which bears said shoe, the operating device acting upon the free ends of the two shoes.

Owing to the fact that the shoes are in contact with the frame over a relatively great length, 35 they are suitably guided and any danger of wedging is eliminated. The tractive force to be exerted by the operating device is thus greatly reduced for a given tension of the network.

In the accompanying drawing, which is given 40 solely by way of example:

Fig. 1 is a partial view of a racket according to the invention, with the network slackened, and showing a longitudinal section of the frame on a level with the network;

45 Fig. 2 is a similar partial section with the network stretched;

Fig. 3 is an enlarged section of the frame on the line 3—3 of Fig. 1;

Fig. 4 is an enlarged longitudinal section of 50 the throat piece, on the line 4—4 of Fig. 1;

Fig. 5 is a partial longitudinal section on the line 5—5 of Fig. 6, of one of the shoes and of a portion of the corresponding flexible band;

Fig. 6 is a corresponding plan view.

55 According to the embodiment illustrated, the

invention is supposed to be applied to a racket having a wooden frame and handle. The frame 1 extends at 1^a to the end of the handle. An axial part 2 forming the throat piece also extends to the rear end of the handle. The extensions 1^a and the part 2 are assembled by cementing and/or by screws. At the exterior and on either side of the throat piece 2 and the extensions 1^a are cemented, in the known manner, reinforcing plates 4 (Fig. 4) consisting of wood, the fibres of which 10 are perpendicular or oblique to the fibres of the parts which they cover. Moreover, a curved piece 5 is cemented, for reinforcing purposes, in the interior of the frame adjacent the throat-piece.

On either side of the throat-piece 2 and substantially as far as the transverse axis of the frame, the said frame 1 is provided on its outer face with a groove 6 (Figs. 1, 2, 3). On either side of the groove 6 the outer face of the frame provides bearing surfaces 7 which are bounded 20 laterally by strips 8 (Fig. 3) which are separately secured to the outer face of the frame. The throat piece 2 is provided with a transverse aperture or passage 9, of rectangular cross section, through which extend the groove 6 and the bearing surfaces 7 at 6^a and 7^a.

The bearing surfaces 7, 7^a, which are situated on either side of the groove 6, 6^a have from A to B, i. e., in the passage 9 and in the adjacent parts of the frame 1, the form of a circular arc whose 30 centre is situated at 0 on the longitudinal axis XX of the racket.

The frame 1 and the throat piece 2, together with the curved piece 5, are pierced with holes 10.

On the bearing surfaces 7, 7^a is slid able, on 35 either side of the axis XX, a traction band 12 which is adapted to support a considerable tension stress (1000 to 1500 kgs. per sq. cm. for instance).

The two bands 12 may consist, for example, of steel of a great tensile strength, and 40 they are sufficiently flexible to fit without difficulty upon the curved part of the frame. The bands 12 are provided with perforations 13 (Figs.

4 and 5) which are formed by a partial punching of lugs which are bent around at 14 and are located in the grooves 6, 6^a in which they are slid able. It should be noted that the said lugs 14 may 45 be eliminated, and in this case small grooved pulleys will be mounted on the small bars left in the bands 12 between the perforations 13.

In the part adjacent the throat piece, each band 12 comprises a shoe 15 having the shape of an arc of the same radius R as the part AB of the bearing surfaces 7, 7^a, so that this shoe 50 55 55 may bear over its whole length upon these

two surfaces on either side of the groove 6 or 6^a. Each of the shoes 15 is rigid, and it consists preferably of an enlarged end of the band 12, this end being bent into a U shape (Figs. 4, 5, 6).

5 Both flanges of each rigid shoe 15 are pierced with an aperture 16, in which is engaged a cylinder 17 having a diametrical tapped hole 18 and thus forming a nut. The two nuts 17 are screwed on two parts 19 and 19^a, threaded in contrary 10 directions of an operating screw, said screw being located in the passage 9. The screw (19, 19^a) has at one end a square part 20, male or female, by which it can be turned by a wrench 21 (Fig. 2). A central collar 22 separates the two parts 19 and 19^a threaded in contrary directions.

15 The network which is carried by the frame and is stretched across the same, consists of a single flexible string 23 (of catgut, cord or wire) which is mounted in zigzag according to two inclined 20 directions which are symmetrical with reference to the longitudinal axis XX of the racket, the two ends of the flexible string being connected by a knot. At one end of each zigzag, the two strands of the flexible string, forming a 25 loop, are inserted through two respective adjacent holes 10 in the frame 1; at the other end of each zigzag, the two strands forming the succeeding loop are inserted not only through two adjacent holes 10 in the frame 1, but also through 30 two adjacent perforations 13 in one of the two flexible bands 12.

35 The stretching is effected by turning the screw (19, 19^a) in the proper direction to bring the two nuts 17 nearer to the longitudinal axis AA of the racket, which nuts will take the position shown in Fig. 2, drawing with them the shoes 15 which are always in close contact with the curved surfaces 7 and/or 7^a, and the said shoes, in turn, will draw the flexible bands 12 in the direction of the 40 arrows f¹ and f² (Fig. 2). The perforations 13 of these bands will thus be displaced with reference to the perforations 10 of the frame 1, thus lengthening the loops of the network 23 which are formed around the lugs 14. The lengthening 45 is accompanied by the general and simultaneous stretching of the entire network 23.

50 In order to slacken the said network, it is simply necessary to turn the screw (19, 19^a) in the other direction, in order to separate the nuts 17 and hence the shoes 15.

55 It should be noted that owing to the fact that the nuts 17 rotate in the shoes 15, these latter will not be subjected to any lateral stress, and will remain in close contact with the curved surfaces 7 and/or 7^a.

As will be observed, the entire operating device is simple and light, and is very easy-working, as there is no effect of wedging in the passage 9.

Owing to the invention, it is possible to give very great tensions to the network, with great facility.

However, in the case of the utilization of the maximum tensions which can be thus obtained, 5 in order to prevent the network from possibly cutting into the frame at the bottom of the groove 6 after a time, it is of advantage to cement on the bottom of this groove 6 a thin strip provided with perforations adjacent the holes 10 and consisting of wood with cross grain, or of any other non-fibrous material synthetic or the like.

Obviously, the said invention is not limited to the embodiment herein described and represented, which is given solely by way of example. The 15 bands 12 might be replaced by chains or by any other flexible or jointed supporting members.

Having now described my invention, what I 20 claim as new and desire to secure by Letters Patent is:

1. A racket for tennis or like games, comprising an open frame with handle, a string network stretched across said frame, two flexible metallic bands bearing flatwise on said frame and positioned symmetrically with respect to the longitudinal axis thereof, said bands having one end adjacent said handle and being adapted to support said network and to slide along the frame, each of said bands comprising at said one end a rigid circularly curved shoe, said frame being formed with a similarly curved bearing surface for each shoe, and means attached to the free end of each shoe and adapted to exert a traction upon said bands to slide them along the frame, whereby said network can be stretched or slackened at will.

2. A racket for tennis or like games, comprising an open frame with handle, a string network stretched across said frame, two flexible metallic bands bearing flatwise on said frame and positioned symmetrically with respect to the longitudinal axis thereof, said bands having one end adjacent said handle and being adapted to support said network and to slide along the frame, each of said flexible bands including at said one end a portion having a greater width than the remainder of the band and the lateral edge portions of which are turned at right angles to the band to form a rigid shoe which is U-shaped in cross section, said shoe being circularly curved in the longitudinal direction, a nut rotatably supported at the free end of said shoe between said upturned edge portions, said frame being formed with a curved bearing surface for each shoe having the same radius as the shoe, and a screw having two parts threaded in contrary directions, each of which is screwed into one nut.

EMILE HENRI AUBERT.
